UNITED STATES PATENT OFFICE.

RAY T. SAVAGE, OF NEW YORK, N. Y.

BUILDING CONSTRUCTION.

1,071,467.

Specification of Letters Patent.

Patented Aug. 26, 1913.

Application filed November 24, 1911. Serial No. 662,250.

To all whom it may concern:

Be it known that I, RAY T. SAVAGE, a citizen of the United States, and a resident of the borough of Manhattan, in the county 5 of New York, city and State of New York, have invented certain new and useful Improvements in Building Construction, of which the following is a specification.

In the use of concrete, which is now employed so largely in structural work, it is usually necessary to construct a mold or form, (which must be substantially water tight) into which the concrete is poured while in a more or less fluid or plastic state. 10 These molds or forms are comparatively expensive (running about 50% of the total cost of the work) and they require expert work in the building and handling of the same. Furthermore, the concrete, after the 15 mold is removed, bears the imprint on its face of any cracks, irregularities or imperfections in the mold, so that for finished work, the face of the concrete has in a great many cases to be entirely resurfaced. It is 20 the object of my invention to wholly obviate the need for any molds or forms, and also to produce a completed structure having a finished exterior, free from the markings of a mold or any other imperfections. 25 Accordingly my invention consists in a preferred form of a building construction comprising blocks laid in inner and outer courses, and a filling of bonding material, such as concrete, which fills up the space 30 between the inner and outer courses and engages in undercut bonding grooves formed on the opposing faces of the blocks of the two courses, whereby to tie the two courses together in a unitary structure. In addition 35 to this, another feature of the invention consists in holding the blocks of the two courses properly spaced during course of construction, by means of spreaders which engage in the bonding grooves in the blocks. 40 Various other features and objects of the invention will become apparent as the specification proceeds.

In the drawings accompanying the specification, I have illustrated several preferred 45 embodiments of the invention but I would have it understood that various changes and modifications may be made therein without departing from the spirit and scope of the invention.

In the drawings: Figure 1 is a broken sectional view of a portion of partially completed wall constructed in accordance with and embodying features of my invention. Fig. 2 is a broken sectional view illustrating a portion of wall and flooring constructed in 50 accordance with the invention. Fig. 3 is a broken detail view, with parts shown in section, to illustrate the wall and floor construction and a form of reinforcement for the floor. Fig. 4 is a perspective view of 55 a preferred form of building block of which the inner courses are made. Fig. 5 is a like view of a special form of block sometimes used where a floor or like structure is to branch off from the wall.

The same reference characters refer to corresponding parts throughout the several views.

For purposes of illustration I have shown in Fig. 1 a portion of wall constructed in 50 accordance with the preferred form of my invention. This wall is made up of inner and outer courses, 1 and 2, respectively, and between which there is poured or deposited a filling of bonding material 3. The 55 two courses each consist of a series of units or blocks 4 which may be laid in any proper and approved fashion. The meeting edges of the blocks are preferably joined in some suitable way, such as by having a tongue 6 on one block enter a groove 5 in the adjoining block. For the purpose of tying the inner and outer courses together, the blocks forming these courses are preferably provided on their inner opposing faces with 60 bonding grooves 7, which grooves are, as shown, preferably undercut and arranged on downwardly extending inclines on the order of "saw-teeth." These bonding grooves are preferably arranged on substantially 65 horizontal lines. This particular formation of bonding groove causes the concrete as it settles of its own weight to be forced more firmly into the grooves, so that as it hardens it will lock the two courses all the more 70 securely. And the settling of the concrete in these "saw-teeth" grooves will serve to draw the two courses of the wall all the more firmly together.

The blocks which I use are preferably 75 molded of concrete and under great pressure, as by means of a hydraulic press, whereby perfect blocks are produced which

are close-grained and possess all the strength needed. These blocks may be molded right on the scene of operation but ordinarily they will be produced in great numbers at a point of manufacture and then shipped to wherever needed.

In constructing a building according to my invention, the blocks will preferably, as illustrated in Fig. 2, be laid in parallel inner and outer spaced courses, and the courses will be braced from the outside at needed points by means of suitable framing 8. This framing may consist simply of a series of uprights which would be spaced apart according to the length of the blocks being used, so as to properly sustain them in place while the concrete is being poured. To maintain the blocks of the two courses in proper spaced relation while the wall is being constructed, I preferably use spreading means, such as the spacers or spacing members 9, which spacers preferably have their ends 10 of such formation as to engage in the undercut bonding grooves in the blocks. Suitable reinforcing means, such as elements 11, may, if desired, be placed in the space between the two courses, as well as any pipes, flues or other conduits. After the reinforcing elements, conduits, etc., are in position, the concrete or other bonding material is deposited or poured in the space between the courses, and as this bonding material hardens, it unites the two courses in a practically unitary structure. The spreaders when thus embedded in the concrete serve to assist in locking the two courses together. If found desirable, the concrete may be poured so as to leave ventilating or air spaces between the inner and outer courses.

In ordinary practice the blocks are laid in courses up to a floor level, and then the blocks are branched off from the inner course at the proper level to produce the floor. For the purpose of branching these floor blocks off from the inner course, a special angular-shaped block 12 is preferably employed. This angular block forms a connection between the horizontally disposed floor blocks and the vertically disposed blocks of the inner course. Concrete, tiling or other flooring material, may then be placed on top of the floor blocks, substantially as indicated at 13, and for the purpose of giving the necessary rigidity and strength to the floor, horizontal reinforcing members 14 may be embedded in the floor. These horizontal strengthening members may be united with the vertical reinforcing elements of the wall, as in the manner indicated at 15. After a floor has thus been laid, the blocks constituting the inner and outer courses may be continued on upward. The first block of the inner course which is above the floor level may be

set right in the flooring material, as indicated in Fig. 2, but if desired, the inner course need not be interrupted at the floor level for by employing a special block, such as shown in Fig. 5, the inner course may be made continuous from top to bottom of the structure. This special block is simply one of the ordinary inner course blocks which is provided with a lateral extension 16 with which the floor blocks unite.

For the purpose of additionally strengthening the floor or roofing portion of the structure, I may provide a truss-work, substantially as illustrated in Figs. 2 and 3, the same consisting of truss reinforcements 80 17 which are embedded in the floor or roofing material. To provide for the reception of these truss members, I preferably employ another special form of block which, as shown at 18, in Fig. 2, consists of a block 85 having oppositely directed angular end portions 19. Two of these blocks, when united, as shown in Fig. 2, form a trough-like pocket for the reception of the reinforcing elements. With the use of these 90 truss reinforcements, a rigid and strong flooring structure is obtained.

It is a well known fact that concrete is not entirely weatherproof and that in damp weather it "sweats" so called. To overcome this objection and to render the structure absolutely dry on its interior, I preferably treat the blocks with a suitable weatherproofing compound. The blocks may be treated on both faces, or only one face of 100 the blocks of either course may be so treated. Preferably, however, and as shown herein, the blocks of the inner course have their innermost face treated to render them waterproof, substantially as indicated at 20. 105 This provision prevents any moisture from seeping through the wall.

In ordinary concrete work it was usually necessary to provide lathing or "furring" on the inner face of a wall to which the 110 plaster or other finishing coat is applied. Another feature of my invention resides in the provision of means whereby no such devices are necessary. To this end the blocks of the inner course are preferably provided 115 on their exposed faces with retaining grooves or corrugations 21 for receiving the plaster or other coating. By this construction I am enabled to apply the plaster or other finishing coat direct to the blocks 120 of the inner course.

The outer face of the outer course blocks may be finished in any desired manner. For instance, they may be finished to represent brickwork, or they may be ornamented in 125 any other way to suit different requirements.

What is claimed, is:

1. In building construction, blocks laid in inner and outer courses, which courses 130

are arranged in spaced relation, the blocks of the two courses having horizontally extending and downwardly inclined undercut bonding grooves of "saw-tooth" formation, 5 spacing members having their ends adapted to engage in the saw-tooth grooves to hold the blocks of the two courses properly spaced during construction, and a filling of concrete between the two courses, said concrete filling entered into the saw-tooth grooves of the blocks to tie the two courses together.

2. In building construction, blocks laid in inner and outer courses, which courses are disposed in spaced relation, the blocks of 15 the two courses having on their inner opposed faces, horizontal downwardly extending undercut bonding grooves, the blocks of the outer course having a finished outer face, 20 the blocks of the inner course having retaining grooves on their exposed face to retain plaster or a like finishing coat and being treated with a waterproofing material on their innermost face to render them impregnable to moisture, and a filling of concrete 25 poured in between the two courses and engaged in the undercut bonding grooves of the blocks to tie the two courses together.

3. In building construction, blocks laid in 30 inner and outer courses, which courses are disposed in spaced relation, the blocks of the two courses having on their inner opposed faces, horizontal, downwardly extending undercut bonding grooves, the blocks of 35 the outer course having a finished outer face, the blocks of the inner course having retaining grooves on their exposed face to retain plaster or a like finishing coat and being treated with a waterproofing material on 40 their innermost face to render them impregnable to moisture, reinforcing elements disposed between the two courses, and a filling of concrete poured in between the two courses and engaged in the undercut bonding grooves 45 of the blocks to tie the two courses together.

4. In building construction, blocks laid in inner and outer courses with a space intervening between the two courses, the blocks of both courses having horizontally extending 50 downwardly inclined undercut bonding grooves on their opposing inner faces, a filling of bonding material between the two courses engaging in and settling naturally by gravity into the downwardly inclined undercut grooves in the blocks to automatically tie the inner and outer courses together, the blocks of the outer course having their outer faces finished to form the outer face of the wall, and the blocks of the 55 inner course having their exposed face provided with horizontally extending grooves to receive a finish coat of plaster or like material.

5. In building construction, blocks having 60 horizontally extending undercut bonding

grooves inclined downwardly and inwardly into the body of the block, said blocks being laid in substantially parallel courses with the bonding grooves of the blocks in one course facing the bonding grooves in the 70 blocks of the opposite course, means for holding the courses in proper spaced relation, and a filling of concrete placed between the two courses while in a plastic state whereby such filling material will flow by 75 gravity down into the downwardly inclined undercut bonding grooves of the blocks in the opposite courses so as to automatically tie the two courses together as the concrete hardens.

6. In building construction, blocks having undercut bonding grooves extending horizontally of the blocks and inclined downwardly and inwardly on a slant into the body of the blocks, the said blocks being 80 laid in spaced substantially parallel courses, with the bonding grooves of the blocks in opposite courses facing each other, spacers having downwardly projecting hooked ends 85 engaged in the bonding grooves of the blocks 90 in the opposite courses to hold the courses properly spaced, and a filling of concrete material filled in the space between the courses while plastic so as to flow by gravity 95 down into the downwardly inclined undercut bonding grooves and in hardening to automatically tie the two courses together.

7. In building construction, blocks laid in inner and outer substantially parallel courses to form a wall, a filling of concrete 100 between the courses, the blocks composing the two courses having horizontally extending and downwardly inclined undercut bonding grooves on their opposing faces to receive the concrete filling which thereby enters into the downwardly inclined grooves to tie the two courses together, the blocks of the inner course extending to a predetermined point and there branching off laterally to form the base for a floor, a layer of 105 concrete on the laterally extending blocks to provide the floor surface, the blocks of the inner course being continued on upward above the floor level to the desired height, suitable reinforcements embedded in the 110 concrete of the wall and floor, and trough-shaped blocks coöoperating with the laterally extending blocks to form hollow girders at predetermined points in the floor for the reception of flooring reinforcements.

8. In building construction, superposed blocks laid in inner and outer courses with a space intervening between the two courses, the blocks forming such courses having in their opposing faces horizontally extending 115 and downwardly inclined undercut bonding grooves of saw-tooth formation, and a filling of concrete placed in the space between the two courses while in a plastic state, whereby the said filling material will of 120 125 130

itself flow down into the downwardly inclined undercut bonding grooves in the blocks so as to automatically tie the blocks constituting the two courses together as the concrete hardens.

Signed at the borough of Manhattan, in the county of New York, city and State of

New York this 22nd day of November A. D. 1911.
